UNITED STATES PATENT OFFICE.

PAUL A. MELVIN, OF CHICAGO, ILLINOIS.

CLAMP FOR CONCRETE FORMS.

Application filed March 11, 1926. Serial No. 93,874.

This invention relates to an improved clamp for concrete or other forms, requiring clamping devices, and refers more particularly to forms for the construction of 5 columns and the like, one of the objects of this invention being to provide clamping means for holding the form, panels or sides in a fixed position while the void is being filled with concrete or other materials, 10 and while same is becoming hardened or set.

A further object is to provide a clamping device of simple construction, and one in which all the parts are intact and 15 inter-changeable, so that no fitting or selection of loose parts or keys of the different sections of this clamp is required preparatory to putting it on the form.

The improved clamp of the present invention may be utilized any number of times 20 without the loss or replacement of parts or keys thereby effecting a great saving in material and labor. Briefly, the clamp of the present invention comprises straps 25 or bars, each unit being preferably reinforced at one end, which is accomplished by return bending a portion of the strap or bar through which the non-reinforced or plain end of an adjacent unit is adapted 30 to be inserted. The outer lateral edge of the plain end of each bar may be provided with meshing elements adapted to mesh with a movable chuck having a center arm provided with similar meshing elements, which 35 in turn are wedged into locking engagement with the meshing elements on the bar by means of a loose non-removable wedge shaped key.

A prime feature of the present invention 40 is the provision of an adjustable chuck and key permanently mounted on the return-bent end of each strap or bar, thus preventing loss of these parts when the clamp is being stripped or transferred from one location to another. The present invention obviates numerous difficulties encountered in 45 various other clamps on the market provided with loose keys, some of said objections being the loss of these keys and the costly 50 operation of punching the hardened concrete drippings from the apertures with which the nails or keys register and the chipping of hardened concrete from the surface of the clamp before the mounted parts 55 are free and adjustable. The present invention requires no jacks or tighteners to posi-

tion the various clamp units, this function being accomplished by means of the chuck and key, thus eliminating a costly tool and several labor operations.

Various other advantages and objects will be more apparent from the following description.

Fig. 1 is a plan view and Fig. 2 a side elevational view illustrating the application 65 of one of my improved clamps installed on a column.

Fig. 3 is an enlarged detail top plan view with the reinforced return-bent end removed to more clearly show the operation of the various parts at one corner.

Fig. 4 is a cross sectional view taken on line 4—4 of Fig. 3.

Fig. 5 is a cross sectional view taken on line 5—5 of Fig. 6 showing taper and meshing elements.

Fig. 6 is an enlarged front view of the chuck looking at its teeth.

Fig. 7 is a detail plan view of a slightly modified construction in which a fixed shim 80 is substituted for the chuck and a non-losable key is provided at the end of the return bend.

Fig. 8 is a cross sectional view taken on line 8—8 of Fig. 7 showing the shim and 85 key in a working position.

Fig. 9 is a plan view of another modified form of construction in which a slotted key abuts the outer edge of the reinforced end of the bar.

Fig. 10 is a cross sectional view taken on line 10—10 of Fig. 9.

Fig. 11 is a cross sectional view taken on line 11—11 of Fig. 10 illustrating the locking device which supports the key.

Referring now more in detail to the drawings and more particularly to Figs. 1 to 6, 1 designates a column form which may be of any shape and which is shown as comprising parts set on edge and mounted 100 adjacent each other. 2 designates as a whole each clamp unit as assembled, which comprises a bar or arm 3 formed of strap metal, one end of which is turned back upon itself as shown at 4 for the purpose of providing a reinforced end and a groove 5 in which to insert the plain end of an adjacent bar. The end of each bar 3 opposite the reinforced end, may be provided on its outer edge with teeth, dogs or similar meshing elements 6 adapted to have locking engagement with a chuck.

Referring more in detail to Figs. 3 to 6, it will be seen that the chuck comprises a metal casting having parallel adjacent sides 8 and a center arm 9. One lateral edge of the center arm 9 is provided with meshing elements 10 which may comprise dogs, teeth or other meshing elements similar to the meshing elements 6 on the bar 3. The opposite lateral edge of said center arm 9 is tapered as shown at 11 for the purpose of adjustment when wedged with the tapered side 12 of the loose non-removable key 13. This loose non-removable key 13 is preferably provided with turned ends 14 which function to prevent loss of key when the clamp is not in operation.

The center arm 9 of each chuck is provided intermediate its length with a closed aperture 9' adapted to receive a locking element such as a cotter pin or the like, which prevents accidental loss of the chuck and key 13 when the clamp is not in use.

It must be particularly noted, that the sides 15' adjacent apertures 16' (Fig. 6) are tapered inwardly to a width corresponding to the width of the meshing elements 10 for the purpose of automatically centering the end of the arm 3 carrying the meshing elements 6.

As another feature of the present invention, the outer edge of the return bent reinforced end of each bar 3 is tapered outwardly at 15 from a point on the return bent end and terminating short of the termination of the end of the return bend. The chuck is similarly tapered as shown at 16, (Fig. 5) the purposes of which will be hereinafter explained. The outer end of each return bend may be provided with the aperture 17 registering with the aperture 18 intermediate the length of each bar 3. The purpose of these apertures 17 and 18 is to permit the insertion of a nail 19 or other temporary locking element after the four corners of the clamp have been temporarily placed in position and the chucks and pins temporarily tightened. This allows a unit of two sections to be raised to position in one operation.

Each bar 3, chuck 7 and key 13 are made uniform in order that they may be used interchangeably, and four units are required to make a complete clamp to surround a rectangular form. It is to be noted that the sides 8 of each chuck 7 project inwardly to contact both the return bent end of each bar as well as the end of the bar immediately there adjacent as shown very clearly in Figs. 1, 3 and 4. The purpose of this is to prevent the reinforced end from enlarging, spreading or being accidentally bent out of position.

In assembling adjacent sections 3 of the clamp, the plain end containing the meshing elements 6 is inserted into the open

groove 5 in the reinforced return bent end of an adjacent bar 3. The key 13 and chuck have been previously adjusted to a released position in groove 5. The meshing elements 6 of bar 3 are then engaged with the meshing elements on the center arm 9 of the chuck.

The tapered edge 12 of the key 13 is then forced against the tapered edge 11 of the center arm 9, tightening the connection between said meshing elements and causing the two ends of adjacent units to be drawn together. This two-way adjustment is accomplished by means of the engagement between the tapered edge 15 on the return bent reinforced end, and the tapered edge 16 of the chuck. As the chuck moves forward on the tapered surface 15, it will act to automatically pull one of the bars 3 with it, while at the same time riding forward on the adjacent bar 3, thus simultaneously adjusting opposite ends of two adjacent bars. The nail shown diagrammatically at 19 may be inserted in the apertures 17 and 18, this nail 19 being temporarily placed therein to form a tight right angle which will facilitate the erection or raising of the clamp in sections or units. It may be here stated that this nail should be removed before stripping, its only object being to facilitate the erection of two engaged units. After the complete clamp has been raised to the height desired, the keys 13 in the corners opposite to those carrying the nails are tightened, and as heretofore explained this operation will serve to draw both ends of adjacent bars together into tight locking engagement, thus accomplishing the result desired. In disassembling and stripping the clamp, it is only necessary to tap the key 105 with a slight blow on its small end, thus releasing the chuck from engagement.

As a feature of the invention, it may be brought out that the bevel or taper 15 shown in the reinforced end of each bar registering with the bevel 16 on each chuck will serve to immediately disengage the meshing elements of the chuck and bar from locking engagement, thus eliminating all friction. The advantages of this will be apparent to those skilled in this art. After the keys have been released by being tapped on their small end, they will be prevented from loss by means of the bent ends 14. The chuck automatically moves out of engagement with the bar 3 to permit of easy stripping. The plain ends are disengagable through the open grooves 5.

The hole 9' in the extension 9 of the chuck is spaced with relation to the taper 15 so that when the chuck has moved forward to the point where the taper 15 ends, the key inserted in the hole 9' will contact the inner edge of the bar thus preventing further outward movement. This functions

to keep both the key and chuck mounted on the reinforced end of each bar at all times while at the same time the chuck or key can be replaced very easily by removing the cotter pin.

It is to be noted that the keys are forced inwardly on a horizontal plane rather than adjusted in a vertical plane. This may be to an advantage because in tightening one corner, it automatically brings the clamp to a level, and does not act to loosen the other corners.

Referring now more particularly to the modification shown in Figs. 7 and 8, 1 designates a column form and 3 designates individual bars or arms, each bar or arm being provided with meshing elements 6 similar to the meshing elements shown in Fig. 1, and also with the return bent reinforced end 4 as shown. Instead of the key being horizontally adjustable in combination with a chuck, I aperture the reinforced end as shown at 17 for the purpose of inserting a key 18 which may take the form of a gooseneck, if desired, provided at one end with the retaining stud 19, its other end being wider than the aperture 17 as shown at 20. The key is preferably of wedge shape, that is, it tapers outwardly from its small end, and is preferably in the form of a gooseneck as shown, in order to retain the key in position on the reinforced end at all times. The operation of this gooseneck form of key is clearly shown in dotted lines in Fig. 8. Adjacent the bend in the reinforced end, the construction shown in Figs. 7 and 8 is provided, or has inserted in the groove formed thereby, a slotted filler 21 functioning as a shim and having a slot equal to the width of the key at its small end. The function of this filler is to provide a smooth slidable surface for the adjacent edge of a bar inserted therein.

Referring more particularly to the modifications shown in Figs. 9, 10 and 11, the column form is shown at 1, and 3 designates adjacent bars or arms of the clamp. One end of the bar 3 is provided with meshing elements 6 such as notches, dogs, teeth or the like, and the other end is provided with the reinforced return bent end 4. In this construction each key 22 takes the form of a centrally slotted key having an edge 23 parallel with the outer edges of each arm 3 and a tapered edge 24 at an angle to the edge of each bar 3. The key is insertable on the plain end of each bar 3 and prevented from accidental displacement and loss by means of the rivet or similar element 25. This key is adjusted on the plain end of each bar 3 against the reinforced end 4 by means of the adjustable locking element 26, which is similar in form to the key 22 being centrally apertured as shown at 27. This locking element is movable in either direction

and adapted to mesh with the meshing elements 6 on the bar 3, thus holding the outer edge of the key in a fixed position ready to be tightened. In assembling, one edge 28 of the locking element 26 is forced into mesh with the meshing elements 6 thus forcing the key 22 against the reinforced end 4 of each bar 3, and in disassembling the other end 29 is tapped to disengage the end 28 from mesh with the meshing element 6, and the key 22 is slidable on the plain end of the bar 3, said plain end of the bar being movable laterally in the groove formed by the return bent end to release adjacent elements from engagement.

It will be immediately obvious that the clamp shown in the present invention eliminates the possibility of loss of keys and the great expense in replacing same, as well as eliminating the various expensive labor operations necessary to clean and remove concrete from the arms and apertures in the standard form of clamp which is now necessary after each operation.

I claim as my invention:

1. A column clamp, comprising connected units, each unit comprising a bar of substantial length, one end of which is return bent and spaced from the body of the bar, the other end on its outer lateral edge being provided with meshing elements, and means movable relative to the return bent end of a bar adapted to engage the meshing elements on the lateral edge of an adjacent bar.

2. A column clamp, comprising connected units, each unit comprising a bar, one end of which is return bent and spaced from the body of the bar, a lateral edge of the other end being provided with meshing elements, and means movable on the return bent end of a bar including a chuck having meshing elements and a wedging pin, functioning with the wedging of the pin to cause the meshing elements on the chuck to register with the meshing elements on a lateral edge of an adjacent bar placed in said spaced return bend.

3. A column clamp, comprising connected units, each unit comprising a bar, one end of which is return bent and spaced from the body of the bar, a lateral edge of the other end being provided with meshing elements, a chuck having meshing elements and wedge non-removably mounted on the return bent end of the bar, and movable in said space between the return bent end and body of the bar against the end of an adjacent bar inserted in said space to mesh with and lock adjacent ends of adjacent units together.

4. A column clamp, comprising connected units, each unit comprising a bar, one end of which is return bent and spaced from the body of the bar, a lateral edge of the other end being provided with meshing ele-

4
ments, a chuck having meshing elements and wedge non-removably mounted on the return bent end of the bar, and movable in said space between the return bent end and body of the bar against the end of an adjacent bar inserted in said space to mesh with and lock adjacent ends of adjacent units together, the chuck and wedge being provided with means preventing accidental displacement from their loosely mounted position on the return bent end when the units are assembled, but permitting ready intentional removal.

5. A column clamp, comprising connected units, each unit comprising a bar, one end of which is return bent and spaced from the body of the bar, a lateral edge of the other end being provided with meshing elements, a chuck having meshing elements and wedge non-removably mounted on the return bent end of the bar, and movable in said space between the return bent end and body of the bar against the end of an adjacent bar inserted in said space to mesh with and lock adjacent ends of adjacent units together, the outer lateral edge of each return bend being tapered for a portion of its length adapted to register with tapered edges on the chuck for facilitating assembly and disassembly.

6. A column clamp, comprising connected units, each unit comprising a bar, one end of which is return bent and spaced from the body of the bar, a lateral edge of the other

35

end being provided with meshing elements, a chuck having meshing elements and wedge non-removably mounted on the return bent end of the bar, and movable in said space between the return bent end and body of the bar against the end of an adjacent bar inserted in said space to mesh with and lock adjacent ends of adjacent units together, the outer lateral edge of each return bend being tapered for a portion of its length adapted to register with tapered edges on the chuck for facilitating assembly and disassembly.

7. A column clamp, comprising connected units, each unit comprising a bar, one end of which is return bent and spaced from the body of the bar, a lateral edge of the other end being provided with meshing elements, and means movable on the return bent end of a bar including a chuck having meshing elements and a wedging pin, functioning with the wedging of the pin to cause the meshing elements on the chuck to register with the meshing elements on a lateral edge of an adjacent bar placed in said spaced return bend, said wedging pin being moved into and out of wedging engagement in substantially a horizontal plane relative to the plane of the column being clamped.

PAUL A. MELVIN.
